UNITED STATES PATENT OFFICE.

DONALD H. THURBER, OF WATERTOWN, MASSACHUSETTS, ASSIGNOR TO MELVIN J. BEAN, OF NATICK, MASSACHUSETTS.

COVER FOR LEAF SPRINGS.

Application filed November 28, 1923. Serial No. 677,409.

To all whom it may concern:

Be it known that I, DONALD H. THURBER, a citizen of the United States, residing at Watertown, in the county of Middlesex and 5 State of Massachusetts, have invented new and useful Improvements in Covers for Leaf Springs, of which the following is a specification.

For proper action it is quite important 10 that leaf springs such as are used on vehicles shall be well lubricated so that the individual leaves may slide smoothly on each other as the spring is flexed. As these springs are positioned where they are exposed to dirt 15 and water it is difficult to maintain them in proper condition.

This invention, therefore, provides a readily attachable and detachable cover for protecting the springs from the access of 20 dirt and water and it is so constructed as to furnish a casing about the spring for the reception of lubricant, such as grease, which is held thereby in constant contact with the several leaves so that it finds its way between them as they are flexed, insuring proper lubrication and entire freedom from 25 rust or other obstruction to their free action.

Beside a construction which furnishes a 30 lubricant-receiving pocket about the spring, the cover is also so constructed as to permit it to be laced in position about the spring in a manner to insure a close joint between the mating edges so that the escape of lubricant 35 and entry of foreign matter is prevented.

For a more complete understanding of this invention reference may be had to the accompanying drawings in which—

Figure 1 is a fragmentary perspective of 40 a leaf spring showing the cover applied thereto and partly laced in position, the unlaced portion being opened up to better show its construction.

Figure 2 is a bottom plan of the same 45 showing the cover fully applied.

Figure 3 is a fragmentary plan showing one end of the cover fully opened out.

Figures 4 and 5 are sections on lines 4—4 and 5—5, respectively, of Figure 3.

50 The cover comprises a main portion or piece 1 preferably of flexible material waterproofed at least on one side. The material known as moleskin is quite satisfactory for this purpose, this material having one water-

proof face and a felt backing on the opposite face. The felt backing is to be positioned toward the spring and furnishes a holding medium to receive the lubricant to present it to the leaves of the spring. The ends of the piece 1 are inwardly turned, as 55 shown at 2 in Figure 5, and embracing the inwardly turned end is a strip 3 of felt, or other suitable material, bent thereover and made fast thereto as by stitching shown at 4. This construction furnishes an end rib 60 projecting from the inner face of the strip 1 which may engage about the spring to retain the intermediate portions of the piece 65 out of contact with the spring and form a pocket for lubricant therearound, the spring 70 projecting through the pocket at either end, the ribs forming in effect stuffing boxes 75 through which the spring passes.

The sides of the piece 1 are also inwardly turned as shown at 5 and through the double 80 layer of material formed thereby are inserted lacing fasteners. As shown these comprise hooks 6. The width of the piece is so proportioned that it may be wrapped about the leaf spring with the edge folds 7 brought 85 into abutting relation. In order to close the joint between the edge folds a supplemental flap or strip 8 is stitched at one end as 90 to the inner edge portion of one of the edge folds and is of sufficient width to bridge under the joint between the edge folds and underlying the other edge fold. This flap, 95 therefore, forms a seal across the joint to retain the lubricant within the pocket and prevent the entrance of foreign matter thereto when the cover is wrapped about the spring, as shown in Figure 1. A lacing 10 is engaged with the opposite rows of lacing hooks 6 to retain the cover in position on the 100 spring.

Having thus described an embodiment of this invention it should be evident that many changes and modifications may be made therein without departing from its spirit or scope as defined by the appended claims.

I claim:

1. A device of the class described comprising a piece of flexible material constructed to be wrapped about a spring intermediate its ends, said piece having its edges where the spring emerges therefrom turned inwardly, and a strip of material folded over 105 said inwardly turned edges and made fast

2
thereto to space the piece from said spring to form a pocket for lubricant surrounding said spring.

2. A device of the class described comprising a piece of flexible material constructed to be wrapped about a spring intermediate its ends, the end edges of said piece where the spring emerges therefrom being inwardly turned and a strip of felt folded about each inwardly turned edge and stitched

thereto to form a thickened rib closely embracing said spring and spacing said piece therefrom, and means for fastening the side edges of said piece to form a closed joint, the whole forming a lubricant-receiving 20 pocket through which said spring passes.

In testimony whereof I have affixed my signature.

DONALD H. THURBER.
